(57) CLAIM

The ornamental design for an outdoor chaise lounge cover, as shown and described.

DESCRIPTION

FIG. 1 is a front perspective view of a first embodiment of an outdoor chaise lounge cover with arms and with gathered skirt showing my new design;

FIG. 2 is a side view thereof;

FIG. 3 is a rear view thereof;

FIG. 4 is a front view thereof;

FIG. 5 is a top plan view thereof;

FIG. 6 is a side view of a second embodiment of an outdoor chaise lounge cover with arms and with straight skirt, the opposite side being a mirror image thereof;

FIG. 7 is a rear view thereof;

FIG. 8 is a front view thereof; and,

FIG. 9 is a top plan view thereof.
